CLAIM

The ornamental design for an abrasive block support, as shown and described.

DESCRIPTION

FIG. 1 is a perspective view of the design.

FIG. 2 is a left side elevational view of the design of FIG. 1.

FIG. 3 is a right side elevational view of the design of FIG. 1.

FIG. 4 is a top plan view of the design of FIG. 1.

FIG. 5 is a bottom plan view of the design of FIG. 1.

FIG. 6 is a front view of the design of FIG. 1; and,

FIG. 7 is a rear view of the design of FIG. 1.

The dotted lines show an environment of the design and do not form a portion of the ornamental design. The dash-dot-dash broken lines in the drawings define boundaries of the claim and form no part thereof.
